US00D729393S

(12) **United States Design Patent**
Dunn et al.(10) **Patent No.:** **US D729,393 S**
(45) **Date of Patent:** **** May 12, 2015**(54) **OUTSOLE FOR AN ORTHOPEDIC DEVICE**(71) Applicant: **Ossur HF**, Reykjavik (IS)(72) Inventors: **Adam Dunn**, Laguna Niguel, CA (US);
Gil David Manalo, San Clemente, CA (US)(73) Assignee: **Ossur HF**, Reykjavik (IE)(***) Term: **14 Years**(21) Appl. No.: **29/486,221**(22) Filed: **Mar. 27, 2014**(51) LOC (10) Cl. **24-04**

Primary Examiner — George D Kirschbaum*Assistant Examiner* — Jennifer Watkins(74) *Attorney, Agent, or Firm* — Workman Nydegger(57) **CLAIM**

The ornamental design for an outsole for an orthopedic device, as shown and described.

DESCRIPTION

FIG. 1 is a perspective view of an outsole for an orthopedic device showing the design;

FIG. 2 is a bottom plan view of the outsole of FIG. 1;

FIG. 3 is a front elevational view of the outsole of FIG. 1; and,

FIG. 4 is a back elevational view of the outsole of FIG. 1.

The broken lines are included for the purpose of illustrating environmental structure and form no part of the claimed design.
